UNITED STATES PATENT OFFICE.

CHARLES LANE GOODRUM, OF PHILADELPHIA, PENNSYLVANIA, ASSIGNOR, BY MESNE
ASSIGNMENTS, TO P. C. BURNS, OF CHICAGO, ILLINOIS.

SELECTIVE ELECTRICAL SIGNALING SYSTEM.

1,026,029.

Specification of Letters Patent. Patented May 14, 1912.

Application filed August 8, 1903. Serial No. 168,717.

To all whom it may concern:

Be it known that I, CHARLES L. GOODRUM, a citizen of the United States of America, and resident of Philadelphia, Philadelphia 5 county, Pennsylvania, have invented a certain new and useful Improvement in Selective Electrical Signaling Systems, of which the following is a specification.

My invention contemplates an improved 10 construction and arrangement whereby a number of signaling devices, such as electric bells, and preferably six in number, may be connected at different points to a pair of line wires, and whereby an operator, such, for 15 example, as a telephone operator located at a different station, may ring any one of said bells at will without ringing the others.

My invention is applicable to signaling 20 systems of various kinds, but it is more particularly adapted for use in connection with telephone systems, and especially in connection with what are commonly known as party line systems, it being necessary, as is well known, in telephone systems of this 25 particular character, to locate several subscribers' stations on one line.

Generally stated, the object of my invention is the provision of a simple, improved and highly efficient selective signaling 30 system.

A special object is to provide an improved construction and arrangement whereby at least six bells may be located on one party line, and whereby these bells may be operated on the well known plus and minus principle.

It is also an object to provide certain details and features of improvement tending to increase the general efficiency and serviceability of a selective signaling system of this particular character. To the foregoing and other useful ends my invention consists in matters hereinafter set forth and claimed.

The accompanying figure is a diagram 45 illustrating a selective electrical signaling system embodying the principles of my invention.

As thus illustrated, my improved signaling system comprises a subscriber's party line L and another and similar line L' . These lines are connected at the central station with the usual spring jacks J and J' . An operator's cord circuit, provided with

the usual answering and calling plugs P and P' , is provided and employed in the 55 well known manner as the means for establishing connection between the lines. Substations or subscribers' stations A , B , C , D , E and F are connected with the line L . Similar substation apparatus is connected 60 with the line L' . The said cord circuit is provided with ringing keys A' , B' , C' , D' , E' and F' , whereby the different subscribers may be selectively signaled. For convenience of illustration, only the signaling apparatus and devices are shown, it being understood that the telephonic apparatus and instruments may be of any suitable, known or approved character.

The nature and advantages of my improved selective signaling system will be best understood by considering the manner in which the operator calls up the different subscribers.

Assuming that the operator desires to call 75 subscriber A , the operation consists in inserting the plug corresponding to the set of selective keys in the spring jack J in the usual manner. The operator then depresses the A' key to ringing position, this closes 80 a circuit from the negative pole of battery X , the other pole of said battery being grounded in any suitable manner, through conductor 1 to conductor 2, thence to contact point 3 of the selective key A' , to the spring 85 4, to conductor 5 and strand 6 of the connecting plug, to the wire 7 of the subscriber's line, thence to conductor 8 to the coil of the relay 9, by conductor 10 to the ground G' , which completes the circuit through the 90 polarized relay 9. This relay is constructed so as to respond positively to a negative current, and retracts its armature 30. At the same time, current flows through conductor 7 to conductor 11, relay coil 12, conductor 95 13 to G' , completing a circuit through relay 12. But relay 12 is so constructed that it does not respond to a negative current. A circuit is also completed from line wire 7 to conductor 14, relay coil 15, conductor 16 100 to ground G' . Relay 15 is, however, so constructed that it responds to current flowing in any direction through its coil. Furthermore, it will be seen that when said circuits are completed, as described, an additional 105 circuit is completed as follows: from the

ground G^2 , to the conductor 17, conductor 18, to the generator 19, conductor 20, conductor 21, contact 22 of the selective key A , to spring 23 of said key, by conductor 24 and cord strand 25 of the connecting cord, by line wire 26, conductor 27 to the ringer coil 28 of the station A, to contact point 29 and armature 30 of the relay 9, conductor 10 to ground G^3 . This circuit is completed by reason of the armature 30 being attracted, as hereinbefore described, and thus closing the circuit at contact point 29, when the bell 28 responds to the current produced by the generator 19. It will be seen that the bells 63 and 85, which are connected to the same side of the line, will not ring for the reason that they are open to the ringing current at the armatures 63 and 87 of the relays 12 and 15. At this time, the relay 12 remains in its normal condition, and the relay 15 attracts its armature, as previously described. It will be seen that the bells at the stations B, D and F will not ring for the reason that ringing current is not supplied to that side of the line.

Should the operator desire to call the subscriber at the station marked B, she places the selective key B' in the ringing position, and thereby completes a number of circuits as follows: first, from the battery X , to conductor 1, to conductor 31, to spring 32, conductor 33, contact point 34, conductor 23, conductor 24, cord strand 25 to line wire 26, conductor 35, coil 36 of the polarized relay 35 at station B, conductor 37 to the ground G^4 . Also from line wire 26 to conductor 38, coil 39 of the relay at station B, conductor 40, ground G^6 ; and from line wire 26 to conductor 41, coil 42 of the relay at station F, conductor 43, to ground G^8 . The relay 36 at station B is of the same construction as the relay 9 at station A and responding positively to negative currents, thus attracting its armature 53. But the relay 39 being constructed to respond to positive currents, remains in its normal position; and relay 42 being constructed to respond to either positive or negative currents, attracts its armature 87. It will thus be seen that a circuit is completed from the ground G^2 , to conductor 17, conductor 18, generator 19, conductor 20, conductor 44, to conductor 45, contact 46 of selective key B^1 , spring 47, conductor 48, contact 49, spring 4, conductor 5, cord strand 6, line wire 7, conductor 50, the coils of the bell 51 at station B, by conductor 52 to armature 53 of the relay at station B, conductor 37 and ground G^4 ; the circuit being closed by means of armature 53 and the conductor 52, as hereinbefore described. It will be seen that the bells 73 and 95 will not ring, as the armature 75 of the relay 39 remains in its normal condition, and the armature 97 of the relay 42 is attracted, thus maintaining an open circuit to the bells 73

and 95. The bell 85 at station E will not ring for the reason that ringing current is only projected through wire 7 of the line.

Should the operator desire to call the subscriber at station C, she depresses the selective key C^1 to the ringing position, when circuits are completed as follows: from the ground G^1 , through the battery Y , the minus or negative side of the said battery being grounded, then through conductor 54, to conductor 55, to contact point 56 to spring 57, to contact point 58, spring 47, conductor 48, contact point 49, spring 4, conductor 5, cord strand 6, line wire 7, conductor 8, coil 9, conductor 10 to ground G^3 . Also from line wire 7 to conductor 11, coil 12 at station C, conductor 13 to ground G^5 ; and from line wire 7 to conductor 14, coil 15 at station E, conductor 16, to ground G^7 . The relay coil 9 being constructed to respond to a minus or negative current will now remain in its normal position, while relay 12 at station C being constructed to respond to a plus or positive current will attract its armature 65, which closes a circuit as follows: from the ground G^2 , by conductor 17 to conductor 18, to generator 19, to conductor 20, conductor 21, contact point 59 of selective key C , spring 60, contact 61, spring 32, conductor 33, contact point 34, spring 23, conductor 24, 95 cord strand 25, to line wire 26, to conductor 62, to the ringer coils of the bell 63 at station C, to contact point 64, armature 65, conductor 13 to ground G^5 , thus completing the circuit through the bell 63 which now 100 responds to the current produced by the generator 19. It will be seen, that the bell 28 will not respond, as the circuit is open at contact point 29; also that the bell 85 will not respond, as the circuit is open at the 105 armature 87 of the relay 15 at station E, and as the armature 87 is attracted to its core by completion of a previously described circuit through said coil 15.

Assuming that the operator desires to call the subscriber at station D, the operation is as follows: the operator depresses the selective key D^1 to the ringing position, when circuits are completed as follows: from the pole of the battery Y , to the conductor 54, to contact point 66 of the selective key D , spring 67, contact 68, spring 60, conductor 61, spring 32, conductor 33, contact point 34, spring 23, conductor 24, cord strand 25, line wire 26, conductor 35, coil 36 of the relay at 115 station B, conductor 37, to the ground G^4 . Also from line wire 26 to conductor 38, coil 39 at station D, conductor 40 to ground G^6 ; and from line wire 26 to conductor 41, coil 42 of the relay at station F, conductor 43 to 120 ground G^7 . It will thus be seen that relay 36 at station B being constructed to respond only to a minus or negative current will remain in its normal position, and that relay coil 39 at station D, being constructed to 125 respond to a plus or positive current will 130

spond to a plus or positive current only will attract its armature 39, closing a circuit as follows: from ground G^2 , conductor 17, to conductor 18, generator 19, conductor 20, to conductor 44, contact point 69 of selective key D^1 , to spring 70, contact 71, spring 57, contact point 58, spring 47, conductor 48, contact point 49 to spring 4, conductor 5, cord strand 6, line 7, conductor 72, the coils of the ringer 73 at station D, conductor 74, armature 75, conductor 40 to the ground G^6 , when the bell 73 responds to the current produced by the generator. At this time, the bells 51 and 95 will not respond to said current as a circuit is not completed through their coils, and as relay 36 remains in its normal condition, and relay 42 attracts its armature 97 on the completion of the circuit already described in connection with the selective key D^1 .

When the operator wishes to call subscriber E, she then depresses the selective key E^1 to the ringing position, when circuits are completed as follows: from the ground G^3 , to conductor 76, conductor 77, contact point 78 of the selective key E^1 , spring 79, contact 80, spring 70, conductor 71, spring 57, contact point 58, spring 47, conductor 48, contact point 49, spring 4, conductor 5, cord strand 6, line wire 7, conductor 8, coil 9, conductor 10 to G^8 . Also from line wire 7, to conductor 11, coil 12, conductor 13, ground G^5 ; and from line wire 7 to conductor 14, coil 15, conductor 16 to ground G^7 . At this juncture, it will be seen that with these circuits there is no current flowing through the coils 9, 12 and 15, and that a circuit is completed through the bell 85 as follows: from the ground G^2 , conductor 17, to conductor 18, generator 19, to conductor 20, to contact point 81 of the selective key E^1 , to spring 82, contact 83, spring 67 to contact 68, spring 60, conductor 61, spring 32, conductor 33, contact point 34, spring 23, conductor 24, cord strand 25, line wire 26, conductor 84, the coils of the ringer 85 at station E, by conductor 86 to armature 87, conductor 16 to ground G^7 , when the bell 85 at station E responds to the current produced by the generator 19.

Should the operator desire to call the subscriber at station F, she depresses the selective key F^1 to the ringing position, and thereby closes a number of circuits as follows: from G^2 , conductor 17, to conductor 88, contact point 89 of selective key F^1 , spring 90, contact 91, spring 82, contact 83, spring 67, contact spring 60, contact 61, spring 32, conductor 33, contact point 34, spring 23, conductor 24, cord strand 25, to line wire 26, conductor 41, relay coil 42, conductor 43 to ground G^8 ; also from line wire 26 to conductor 38, coil 39 of relay at station D, conductor 40 to G^6 , also from line wire 26, to conductor 35, coil 36 of relay

at station B, conductor 37 to the ground G^4 . It will be seen that there is no current flowing through the coils 36, 39 and 42, and consequently the relays of said station remain in their normal positions. A further circuit is closed through bell 95 at station F as follows: from the ground G^2 , conductor 17 to conductor 18, generator 19, conductor 20, conductor 44, to spring 92 of the selective key F , contact 93, spring 79, contact 80, spring 70, contact 71, spring 57, contact point 58, spring 47, spring 48, contact point 49, spring 4, conductor 5, cord strand 6, line wire 7, conductor 8, coils of the bell 95 at station F, conductor 96, armature 97 of the relay 42, conductor 43 to ground G^8 , when the bell 95 responds to the current produced by the generator 19.

Thus it will be seen that even with six subscribers on a line my improved apparatus is capable of being employed for selectively signaling any one of these subscribers, and notwithstanding the fact that the signaling is done with positive and negative currents—that is to say, on the well known plus and minus principle.

It will be understood that the resistance of the various relays, and the construction of the various devices, can be modified or changed to suit the conditions of any particular case, and without departing from the spirit of my invention.

What I claim as my invention is:

1. A selective electrical signaling system, comprising a pair of line conductors, six sub-station equipments connected with said line conductors, each equipment including a relay and a bell, a spring jack connected with said line conductors, an operator's cord circuit provided with six ringing keys, a grounded battery having its negative pole connected with the open contacts of two of said keys, another grounded battery having its positive pole connected with the open contacts of another pair of said keys, the relays at two of said substations being adapted to be operated by minus current only, the relays at two other substations being adapted to be operated by plus current only, and a generator having one pole connected with open contacts of all of said keys, the other pole of said generator being grounded and also connected with open contacts of the remaining two keys, and the relays of the remaining two substations being adapted to be operated by both plus and minus current substantially as set forth.

2. A selective electrical signaling system, comprising a pair of line conductors, six substation equipments connected with said line conductors, each of said equipments including a relay and a bell, the bell being connected with one line conductor and the relay with the other line conductor, a spring jack connected with said line conductors, an

operator's cord circuit provided with a plug adapted to be inserted in said jack, said cord circuit being provided with six ringing keys, the relays at two substations being 5 adapted to respond to minus currents, the relays at two other substations being adapted to respond to plus currents, the relays at the remaining two substations being responsive to both plus and minus currents, the apparatus 10 by which the operator at the central station operates the system, for the purpose of calling the different subscribers, comprising a plurality of ringing keys, an alternating current ringing generator having one pole grounded, having both of its poles connected with said ringing keys, and grounded batteries for supplying the plus and minus currents for energizing the relays, substantially as set forth.

20 3. A selective electrical signaling system, comprising a pair of line conductors, six substation equipments connected with said line conductors, each of said equipments including a relay and a bell, two of said relays 25 being polarized and adapted to respond only to minus currents, two other of said relays being polarized and adapted to respond only to plus currents, the remaining two relays being responsive to both plus and minus 30 currents, six ringing keys and means for connecting the same with the line conductors, so as to selectively energize said polarized relays and thereby close the circuits of the bells associated with these polarized relays, and at the same time open the circuits 35 of the bells associated with the said remaining two relays, the apparatus by which the operator at the central station operates the system, for the purpose of calling the different 40 subscribers, comprising a plurality of ringing keys, an alternating current ringing generator having one pole grounded, having both of its poles connected with said ringing keys, and grounded batteries for supplying the plus and minus currents for energizing the relays, substantially as set forth.

45 4. A selective electrical signaling system, comprising a pair of line conductors, two polarized minus relays connected between the ground and opposite sides of the line circuit, two polarized plus relays connected between ground and opposite sides of the line circuit, two relays responsive to both plus and minus currents connected between 50 ground and opposite sides of the line circuit, the apparatus by which the operator at the central station operates the system, for the purpose of calling the different subscribers, comprising a plurality of ringing keys, an 55 alternating current ringing generator having one pole grounded, having both of its poles connected with said ringing keys, and grounded batteries for supplying the plus and minus currents for energizing the relays, substantially as set forth.

60 5. A telephone system comprising a central office, telephone lines leading therefrom, a series of calling instruments normally in circuit with said lines, a series of calling instruments normally out of circuit therewith, 70 and means controlled by central for cutting the first mentioned series of instruments out of circuit with said lines and for cutting in circuit therewith the second mentioned series of instruments, the apparatus by which the 75 operator at the central station operates the system, for the purpose of calling the different subscribers, comprising a plurality of ringing keys, an alternating current ringing generator having one pole grounded, having both of its poles connected with said ringing keys, and grounded batteries for supplying the plus and minus currents for energizing the 80 relays, substantially as set forth.

6. A telephone system comprising a central office, telephone lines, a series of calling instruments normally in circuit with said lines and two series of calling instruments normally out of circuit with said lines, and means for cutting out of circuit with said 85 lines the first mentioned series of instruments and simultaneously cutting in circuit with said lines either of the second mentioned series of instruments, the apparatus by which the operator at the central station 90 operates the system, for the purpose of calling the different subscribers, comprising a plurality of ringing keys, an alternating current ringing generator having one pole 95 grounded, having both of its poles connected with said ringing keys, and grounded batteries for supplying the plus and minus currents for energizing the relays, substantially as set forth.

7. A telephone system comprising a central office, telephone lines leading therefrom, a series of calling instruments normally in circuit with one of said lines, a series of calling instruments normally out of circuit with one of said lines, and means controlled by 105 central for cutting the first mentioned series of instruments out of circuit with their line and for cutting the second mentioned series of instruments into circuit with their line, the apparatus by which the operator at the 110 central station operates the system, for the purpose of calling the different subscribers, comprising a plurality of ringing keys, an alternating current ringing generator having one pole grounded, having both of its 115 poles connected with said ringing keys, and grounded batteries for supplying the plus and minus currents for energizing the relays, substantially as set forth.

8. In a telephone system, a party line, 125 comprising only two wires for talking and signaling, one or more grounded ringers normally in closed bridge of said line, one or more ringers in open bridge of said line, one or more of said ringers having a normally 130

closed conducting path to ground, one or
more of said ringers having a normally open
conducting path to ground, and means re-
sponsive to direct current flowing over
either of said lines for initially closing the
said normally open bridges and conducting
paths.

Signed by me at Philadelphia, Philadel-
phia county, Pa., this first day of August,
1903.
